UNITED STATES PATENT OFFICE

JOHN H. KELLEY, OF LANGLEY, SOUTH CAROLINA

ADJUSTABLE PITMAN FOR LAYS OF LOOMS

Application filed November 18, 1929. Serial No. 406,900.

This invention relates to looms and more particularly to a pitman or connecting arm which extends between the crank shaft and lay of a loom and imparts movement to the lay when the loom is in operation. When a loom is in operation, the lay is swung back and forth by a pitman or connecting arm extending between the lay and a crank shaft and pivotally mounted at its ends to the lay and shaft. After the loom has been in operation for some time the ends of the pitman become worn and since it is necessary for this wear to be compensated for it is now customary to pivotally connect one end of the pitman with the lay by means of a pivot pin having an eccentric portion which passes through the pitman. This has been found unsatisfactory as very often sockets to receive set screws carried by bearings in which the pin is mounted do not properly register with openings through which set screws in the bearings are passed and it is then very difficult to firmly secure the eccentric pin in an adjusted position and often a bearing will be broken by the strain exerted when the screw is tightened.

Therefore, one object of the invention is to provide a pitman or connecting arm so constructed that the use of an eccentric pin is eliminated and at the same time allow the pitman to be adjusted in order to compensate for wear when necessary.

It is also very important that the distance between the axis of the crank arm and the pin connecting the other end of the pitman with the lay remain the same and, therefore, another object of the invention is to so form the pitman that when adjustment is necessary to compensate for wear at the ends of the pitman the pitman itself may be longitudinally adjusted until its end portions have proper fit about the pin and crank arm of the shaft and thereby restore the pitman to its original length.

Another object of the invention is to provide a pitman for looms in which end sections thereof are adjustably connected by a screw having oppositely threaded stems received in threaded openings of the two sections and allow the adjusting screw to be

firmly secured in a set position after an adjustment has been made thereby preventing the screws from accidentally moving.

Another object of the invention is to so construct the pitman that elements now forming part of a pitman already in use may be employed and thereby allow a pitman of a conventional construction to be easily converted into a pitman of the improved construction.

The invention is illustrated in the accompanying drawing, wherein

Fig. 1 is a view showing the improved pitman or connecting arm applied to a loom of a conventional construction,

Fig. 2 is an enlarged view showing the improved pitman principally in side elevation and partially in section,

Fig. 3 is a longitudinal sectional view through the pitman taken on the line 3—3 of Fig. 2, and

Fig. 4 is a transverse sectional view through the screw connecting the two sections of the pitman, the view being taken on the line 4—4 of Fig. 3.

In Figure 1, there has been shown a portion of a loom. This loom, which is indicated in general by the numeral 1, is of a conventional construction and includes the usual lay 2 and crank shaft 3. A bearing is carried by the lay 2 and includes a pair of ears 4 between which fits one end of a connecting arm or pitman 5 which extends between the lay and the crank shaft so that when the crank shaft is rotated by the gears 6 and 7 swinging movement will be imparted to the lay. A pivot pin 8 is carried by the ears 4 of the bearing upon the lay to pivotally mount one end of the pitman but this pin instead of being of an eccentric formation has its intermediate portion 9 concentric to its portions 10 and 11 which are received in the ears of the bearing and the pin is retained in place by a nut screwed upon its reduced and threaded end 12.

Referring to Figures 2 and 3, it will be seen that this improved pitman or connecting arm consists of end sections 13 and 14 which are formed of wood and at their outer ends are recessed to form arcuate seats

15 and 16 so that the ends of the pitman may fit snugly against the intermediate portion 9 of the pitman pin and crank arm of the crank shaft 3. U-shaped yokes 17 and 18 extend longitudinally of the end sections of the pitman and have their arms formed with opposed slots 19 through which extend bolts 20 serving to securely hold the yokes in proper engagement with the end sections 10 of the pitman. Since the arms of the yokes are formed with longitudinally extending slots, they may be adjusted longitudinally until the pivot pin and crank arm of the shaft 3 fit snugly between the yokes and 15 the ends of the sections 13 and 14 and the securing nuts 21 then tightened to firmly hold the yokes in their adjusted positions. The end portions of the arms of the yokes are bent outwardly, as shown at 22 and 23, 20 to form feet through which are passed bolts 24 each of which carries inner and outer nuts 25 and 26 so that by tightening or loosening the nuts the yokes may be moved toward or away from each other and thereby 25 cause the bridge portions of the yokes to engage properly about the pivot pin and crank shaft. The arms of the yoke 18 may terminate in spaced relation to the inner end of the pitman section 14 or flush with its inner 30 end but it is important that the arms of the yoke 17 project beyond the inner end of the pitman section 13 for a purpose to be hereinafter set forth.

In order to adjustably connect the two sections of the pitman, there has been provided an adjusting screw 27 which is disposed between these sections and consists of a boss 28 from opposite sides of which extend threaded stems 29. These stems are oppositely threaded and are engaged through correspondingly threaded openings 30 formed through caps 31 and 32 which are secured upon the inner ends of the two sections 13 and 14 by arms 33, and by referring 45 to Figure 3 it will be seen that the arms are firmly secured against opposed faces of the pitman sections by rivets or equivalent fasteners 34. Therefore, the caps will be firmly held in place and at the same time 50 their arms may constitute reinforcements for the pitman sections and together with the arms of the yokes greatly strengthen the pitman and prevent danger of its sections being broken by strain in case a loom should 55 jam in operation. Sockets 35 are formed in the inner ends of the pitman sections to receive the ends of the stems 29 and thereby allow the two sections of the pitman to be drawn toward each other the full extent of 60 the stems. By referring to Figure 2, it will be seen that the portions of the arms of yoke 17 which extend beyond the cap at the inner end of the pitman section 13 overlap the boss 28. Therefore, after an adjustment 65 has been made and the bolt is tightened to

draw the arms of this yoke toward each other their free ends will be moved into tight gripping engagement with the boss and firmly clamp the boss between them. This causes the boss to be firmly gripped and the screw will be prevented from accidental turning and causing the pitman sections to be moved out of an adjusted position. The annular edge face of the boss is preferably roughened, as shown in Figure 2, so that it may be easily gripped and turned, and in order to allow a turning rod to be engaged with the boss for easy adjustment of the screw, there has been provided sockets 36. Certain of these sockets are connected by 70 passages 37 which extend diametrically through the boss and intersect, as shown in Figure 4, so that as an additional precaution against slipping of the screw a wire may be 75 threaded through the boss and twisted tightly about the arms of the yoke 17.

When this pitman is in use, the yoke 17 is engaged about the crank of the shaft 3 and the pivot pin 8 passed through the yoke 18. The bolts 24 are set in place and tightened to draw the yokes toward each other until the bridge portions of the two yokes fit snugly about the pivot pin and crank after which the screw 27 is rotated to move the pitman sections 13 and 14 longitudinally until the pivot pin and crank fit snugly in the seats 15 and 16. The bolts 20 are then tightened to firmly bind the yokes against the pitman sections and when the bolt which passes through the arms of the yoke 17 is tightened this yoke will have its arms drawn into tight gripping engagement with the boss of the adjusting screw. Therefore, the adjusting screw will be firmly gripped and held against accidental turning. As previously explained, a securing wire may be threaded through the boss and tightly twisted about one arm of the yoke. After the loom has been in operation for a certain length of time the ends of the two sections 100 become worn to such an extent that the pivot pin and crank of the shaft fit loosely in the ends of the pitman. It is then necessary to compensate for this wear, and in order to do so, the bolts 20 are loosened and the adjusting screw turned in a direction to move the pitman sections away from each other until they again bear properly against the pivot pin and crank. The bolts 20 are then again tightened and the loom is ready for 105 operation. It will thus be seen that it is not necessary to remove the pitman from the loom in order to adjust it and also that a very fine adjustment may be made and the pitman restored to its original length. Therefore, the distance between the axis of the pin 8 and the axis of the crank shaft 3 may be retained the proper length to 110 insure correct throw of the lay.

Having thus described the invention, I claim:

1. A pitman comprising end sections, each having a threaded bore extending longitudinally from its inner end, yokes straddling said sections and having arms provided with outstanding feet at their inner ends, the arms of one yoke extending beyond the inner end of the pitman section straddled thereby, an adjustable connection for said pitman sections consisting of a boss disposed between the sections and oppositely threaded stems extending from said boss and engaged in the threaded bores of the sections, said boss being overlapped by the extended ends of the elongated yoke, bolts passed through the pitman sections and arms of said yokes to draw the arms into binding engagement with the pitman sections and bars, and bolts extending through the feet of said yokes.

2. A pitman comprising end sections, heads for the inner ends of said sections formed with threaded openings, an adjustable connection between said sections consisting of a boss having oppositely threaded stems extending from opposite sides thereof and engaged through the openings of said heads, yokes straddling the pitman sections and having bridge portions projecting from the outer ends of the pitman sections and arms engaging opposed faces thereof and provided with outstanding feet at their inner ends, the arms of one yoke overlapping said boss, bolts passed through the feet of said yokes to effect longitudinal adjustment of the yokes, and bolts passed through the pitman sections and arms of the yokes to bind the yokes in adjusted positions upon the pitman sections and cause the boss to be gripped between the arms of the yoke overlapping the same and secure the adjustable connection in a set position.

3. A pitman comprising end sections, heads for the inner ends of said sections formed with threaded openings and having arms extending along and secured against opposed faces of said sections to secure the heads and reinforce the pitman sections, the outer ends of said sections being recessed to form arcuate seats, an adjustable connection between said sections consisting of a boss and oppositely threaded stems extending therefrom and engaged through the openings in said heads, yokes straddling said pitman sections and each having arms bearing against opposed faces of the sections between the arms of said heads, the arms of said yokes being formed with longitudinally extending slots and having their free inner ends bent outwardly to form feet, the arms of one yoke extending to overlap said boss, bolts passed through said feet to adjust the yokes longitudinally, and bolts

passed through the pitman sections and slots of said yoke arms to draw the arms towards each other for tight binding engagement with the pitman sections and boss.

In testimony whereof I affix my signature.

JOHN H. KELLEY.
